UNITED STATES PATENT OFFICE.

WILLIAM H. WINTERBORNE, OF SAN ANTONIO, TEXAS, ASSIGNOR TO SAN ANTONIO MACHINE & SUPPLY CO., OF SAN ANTONIO, TEXAS, A CORPORATION OF TEXAS.

DOUBLE-STROKE PUMPING-JACK.

1,132,538.

Specification of Letters Patent. Patented Mar. 16, 1915.

Application filed July 1, 1912. Serial No. 707,132.

To all whom it may concern:

Be it known that I, WILLIAM H. WINTERBORNE, a citizen of the United States, and resident of San Antonio, county of Bexar, 5 State of Texas, have invented a certain new and useful Improvement in Double-Stroke Pumping-Jacks, of which the following is a specification.

This invention relates to pumps generally 10 and more particularly to a double stroke pumping jack in which two pistons working in the same cylinder are arranged to discharge a steady stream of water therefrom. In pumping mechanism of this character it 15 has been the general practice to mount the pump operating means, such as crossheads, guides, etc., beneath the base frame. Such a construction is objectionable because it is impossible to remove the pump rods, pistons, pipe and cylinder without moving the 20 jack from its foundation.

One of the objects of the present invention is to provide an improved simple and inexpensive construction whereby the pipe 25 cylinder and pistons may be conveniently and readily removed for repairs or cleaning.

Another object is to minimize the power required to operate the pump by more 30 perfectly balancing the parts, arranging improved guides and crossheads to keep the rods in alinement at all times and connecting such operating means thereto as to provide approximately a straight line lift.

35 Other objects and the novel features of the invention will be apparent from the following description taken in connection with drawings, in which,

Figure 1 is a side elevation of the pumping jack, parts being broken away; Fig. 2 40 is a plan view of the same, parts being broken away, and Fig. 3 is an end elevation of the same, parts being broken away and shown in section.

45 Referring to the drawing, there is provided a base frame preferably of cast iron comprising opposite side members 10 and 11 integral with and mounted on a bottom member 12. The bottom member 12 has an 50 opening 13 therein which is approximately centrally located. Centrally in line with the opening 13 and depending from the bottom 12 there is a pump cylinder 14 having flanges 15 at its upper end resting on the 55 bottom of the base frame. The pump cyl-

inder is connected to a T-head 16 one of the openings of which discharges into the outlet pipe 17 which passes through an opening 18 in the end of the frame.

Two plungers 19 and 20 provided with 60 the necessary valves operate within the cylinder 14. The plunger 20 has a solid piston rod 21 connected thereto which passes through a tubular piston rod 22 connected to the plunger 19. The two piston rods extend upwardly above the base frame and through a cap 23 upon the T-head 16. The cap 23 is provided with a stuffing box to prevent leakage past the outer piston rod 22.

The upper edges of the side members 10 70 and 11 of the base frame are provided with bearings for the shafts 24, 25 and 26, which shafts are mounted in the side frame members 10 and 11 and extend a slight distance beyond the same. The shafts 24 and 26 are 75 at opposite ends of the frame members and the shaft 25 is parallel to and intermediate the other shafts. Shaft 24 has mounted thereon the pulleys 27 and 28 which pulleys are located between the frame members and 80 on the outer ends of the shaft are keyed the operating pinions 29, 29. The shaft 25 has the gears 30, 30 keyed to the outer ends of the same and the drive pinions 29, 29, mesh with said gears. Each of the gears 30, 30, 85 has spokes which are provided with the crank pin bearing sleeves 31, 32 and 33, located at different distances from the hub at the center, whereby variable strokes of the pitmen and pump rods connected thereto may be obtained.

The gears 34, 34, keyed to the opposite ends of the shaft 26 mesh with and are operated by the gears 30, 30. The gears 34, 34, 90 are substantially of the same construction as the gears 30, 30.

In order that the stroke of the pump rods may be the same, the pitmen for both pump rods are connected to pins in corresponding crank pin bearing sleeves and in order that 100 both pistons shall not reach the end of their strokes at the same time, the crank pin of one is set slightly in advance of the other.

Supported by the side members 10 and 11 105 and rising vertically therefrom are guide rods 35, 35. The guide rods 35, 35, are opposite the opening 13 in the bottom of the frame and constitute guiding means for crossheads 36 and 37 connected respectively to the outer ends of the pump rods 21 and 110

22. The crossheads 36 and 37 are of substantially the same construction. However, the crosshead 37 is provided with a stuffing box 38 to prevent leakage between the two 5 piston rods 21, 22. The crosshead 37 is provided with bearing pins 39 at its ends and by means of pitmen 40 pivoted on bearing pins 39 the crossheads are connected to crank pins 41 in bearing sleeves 31 on the 10 gears 30. In a similar manner pitmen 42 depending from bearing pins 43 at opposite ends of the crosshead 36 connect the said crosshead to crank pins 44 in bearing sleeves 31' on the gears 34, 34. The rotation of the gears 30, 30, and the gears 34, 34, by the pinions 29, 29, will reciprocate the crossheads 36 and 37 with the pump rods and pistons connected thereto along the guides 35, 35, in opposite directions.

20 Intermediate the ends of the crossheads there are bearing openings 45 therethrough which admit the guide rods 35, 35. At the center of each crosshead there is an enlarged opening 46 centrally in line with the 25 pump rods in which there is disposed a sleeve 47. The sleeve 47 is of such a size and arranged so that the piping, pump rods and pistons may be removed vertically therethrough without removing the crosshead.

30 On the opposite ends of the frame members 10 and 11 there are lugs 48, 49, each lug having an opening therethrough to accommodate the reduced and threaded end of brace rods 50. The brace rods are bolted to 35 the said lugs and extend upwardly and terminate near the upper ends of the guide rods 35, 35, inclining toward the same. The upper ends of the guide rods and brace rods are reduced and threaded and receive a plate 40 51 which has holes therein to fit over the reduced ends of the said guide rods and brace rods so that the same may be bolted to these rods and rigidly connect them together. The plate 51 has a recess 52 in the side thereof 45 so that piping and rods may be removed past the same without necessitating the removal of the plate.

From the foregoing description the operation of the device will be apparent. It will 50 be seen that I have provided an improved pumping jack of an entirely new design which is simpler in construction than other jacks and provides for easy access to the parts of the pumping outfit. The double 55 guides and crossheads are arranged to keep perfect alinement at all times and each crosshead being connected to two connecting rods or pitmen and two gears provides almost a straight line lift. The crossheads are also 60 constructed so that the pumping rods may be removed in a few minutes when clearing out the well or making repairs and the pipe and cylinder may also be drawn out without removing the jack from its foundation. By 65 arranging the device so that the piston rods

extend upwardly from the gear wheels or operating mechanism the foregoing arrangement is possible.

It will be apparent that various changes 70 may be made in the construction without departing from the spirit of the invention and therefore it is not desired that the invention be limited to the exact details as shown and described.

Having described the invention what is 75 claimed is:—

1. In a pumping jack, the combination of three parallel shafts, a pair of meshing gears supported on two of said shafts, a pinion on the third shaft meshing with one of said 80 pair of gears, driving means for said third shaft, guiding means extending above the shafts, two cross-heads substantially equal in size and located above the shafts and gears and movable along said guiding means, rods 85 connecting with ends of the cross heads and the meshing gears, and a pump rod attached to each cross head and extending below the shafts and gears.

2. In a pumping jack, the combination of 90 a base frame comprising spaced vertical side members and a bottom member connected with said side members, three parallel shafts supported at the upper edges of the side members, meshing gears supported in pairs 95 at the outer ends of two of said shafts outside of said side members, a pinion mounted at each end of the third shaft and meshing with one of each of said pairs of gears, driving means for said third shaft extending between said side members, guiding means rising from said base frame, cross heads movable along said guiding means, connecting rods extending between the cross heads and the gears and disposed outside of said guiding means, and a pump rod attached to each 100 cross head.

3. In a pumping jack, the combination of 110 a base frame comprising spaced vertically arranged side members and a bottom member connected to said side members and having an opening extending therethrough, two shafts supported at the upper edges of the side members and extending beyond said 115 side members, a gear mounted at the outer end of each of said shafts, the corresponding gears on the same side of the frame meshing with one another, a third shaft supported at the upper edge of the side members and parallel to the before mentioned shafts, a pinion mounted at each end of the 120 third shaft and meshing with one of each of said pairs of meshing gears, driving means mounted on said third shaft and extending between said side members, guiding rods rising vertically from the frame, cross heads 125 slideable along said guiding rod, a pair of pitmen connected to the opposite ends of each cross head and to the gears mounted at the opposite ends of the same shaft, and con- 130

centrically arranged pump rods connected to said cross heads and extending through the opening in the bottom member.

4. In a pumping jack, the combination of
5 a base frame comprising spaced vertically arranged side members and a bottom member connected with said side members, shafts supported at the upper edges of said side members, a gear mounted at each end of
10 one of said shafts, a pinion mounted at each end of the other of the shafts, said pinions meshing with said gears, driving means connected to the pinion supporting shaft and extending between said side members, guiding means rising vertically in the base frame, a cross head movable along said guiding means, rods connecting said gears with the cross head to operate the same, a

pump rod depending from said cross head, a piston carried by said pump rod, a cylinder 20 for said piston disposed in line with the pump rod, means extending from the side members of the frame to the upper end of said guiding means to brace the latter, and a plate connecting said bracing means and 25 guiding means at their upper ends and provided with an opening to permit the withdrawal of the pump rod, piston, and cylinder without dissembling the jack.

In testimony whereof I affix my signature 30 in presence of two witnesses.

WILLIAM H. WINTERBORNE.
